M. BEVERLY

FLOUR SIFTER AND LIGHTENER

Filed Jan. 8, 1923

Patented May 19, 1925.

1,538,020

UNITED STATES PATENT OFFICE.

MARCELLA BEVERLY, OF DALLAS, TEXAS.

FLOUR SIFTER AND LIGHTENER.

Application filed January 8, 1923. Serial No. 611,469.

To all whom it may concern:

Be it known that I, MARCELLA BEVERLY, a citizen of the United States, residing at 5019 Lindsley Ave., Dallas, in the county of Dallas and State of Texas, have invented certain new and useful Improvements in Flour Sifters and Lighteners, of which the following is a specification.

This invention relates to sifters, and especially an improved flour sifter and lighterener.

The main object of this invention is to generally improve on devices of this character.

Other objects and desirable features will be pointed out or implied in the following details of description, in connection with the accompanying drawings in which:—

Fig. 1 is a top plan view of my improved device; Fig. 2 is a vertical sectional view through the center of the device; and Fig. 3 is a detail view of a portion of one of the rings that carry the cross-bars or beaters that lighten the flour.

The invention consists in the construction and arrangement or combination of parts which will now be fully described in connection with the accompanying drawings in which similar reference characters correspond to similar parts throughout the several views:—

A hollow cylindrical open-ended body or shell 5 is provided with annular beads 6 whose inner surfaces form annular tracks or guides in which are seated rings 7 which are movable circumferentially, but not movable axially. Each of these rings 7 is united with a pair of cross-bars or crossed bars whose centers are apertured at 9, and these centers register with one another at the center of the respective rings 7 and of the cylinder 5.

A wire or rod 10 is bent at opposite ends of its middle portion which forms a handle 11, and from this handle it extends to the center of the cylinder where it is bent and extends axially towards the bottom of the cylinder, and its end portions 12 are thus axially aligned and pass through the respective pairs of openings 9 at their centers and are there secured by solder or any appropriate means. These portions 12 also pass through central openings in two other pairs of crossed bars 13 which may be properly called sifting members, being movable on or immediately above screens 14 of wire-

mesh. The upper one of these screens is secured to the inner surface of the cylinder or shell 5 by any appropriate means; but the lower one is preferably secured to a removable sheet-metal ring 15 which is frictionally or otherwise held in the shell 5 and provided with an annular channel 16 which receives the lower edge of the shell 5 so as to stiffen the bottom of the device and prevent the screen from bearing too hard against the lower sifter-bars 13, these latter being secured to the lower part 12 by any appropriate means. The outer flange of the channel 16 also serves as a hand-hold by means of which the ring 15 can be withdrawn from the shell 5 for removing any lumps or foreign matter that might have gotten through the upper screen. It should be understood that one or more other removable screens may be added under these screens, or that fixed screens may be added with the provision of a door or doors in the shell for removal of the lumps and foreign matter; also, that additional beaters and sifter-members may be added for the additional screens, and these may be secured to or attached to the member 10 in any appropriate way.

The member 10 extends through slots 17 of the shell 5, also through openings 18 of covers or strips 19 which are slidable through openings between the wall of the member 5 and an upper and lower strap or guide 20. The strips 19 cover the slots 17 and prevent the waste of flour therethrough. A supporting handle 21 is provided and secured on the opposite side of the shell 5 from the operating handle 11, and when the device is supported or held in place by the handle 21, the handle 11 can be oscillated for oscillating the several sets or pairs of crossed bars, and during this operation the member 10 moves along the slots 17, and the members 19 move behind the guides 20. If flour is in the device when thus operated, it will be beaten or stirred and thus caused to pass through the screens 14 and thus become sifted, and lightened in regard to its mass.

It is not intended to limit this invention to the exact construction and arrangement here shown and described, but changes may be made within the scope of the inventive idea as implied and claimed.

What I claim as my invention is:—

1. In a sifter, the combination of a cylindrical shell having an annular groove or

track in its wall, a ring seated in the groove for circumferential movement and held against axial movement, a bar or beater secured to the ring, an operating handle provided with means to secure it to the beater, a screen below the beater, and a sifter member immediately above the screen and provided with means securing it to the operating handle.

10. 2. In a sifter, the combination of a cylindrical shell provided with upper and lower annular tracks, upper and lower beaters provided with guiding means mounted to travel along said tracks, an upper screen under the upper beater, a lower screen under the lower beater, a sifter-member between the upper beater and upper screen, a sifter-member between the lower beater and the lower screen, said shell being provided with

20 a slot above the upper screen and a slot between the upper and lower screens, and an operating handle provided with elements extending inward through these slots and having traveling movement in the slots, the inner ends of the said elements being secured 25 to said beaters and said sifter-members, substantially as shown.

3. The structure defined by claim 2, the lower screen being provided with supporting means which includes a ring whose upper part is fitted removably in the lower end of the shell, the lower end of said ring being provided with a channel which receives the lower end of the shell and also provides a hand-hold, substantially as 30 35 shown, for the purposes specified.

In testimony whereof I affix my signature.
MARCELLA BEVERLY.
